BYERS W. KADEL, OF BALTIMORE, MARYLAND

CAR-DOOR MECHANISM

Application filed May 3, 1928. Serial No. 274,844.

My invention relates to door mechanism for railway cars and is especially suitable for application to cars having hoppers disposed on opposite sides of the car center sill, although it may advantageously be employed on cars of other types.

The principal object of the invention is to provide simple and reliable door locking means which serve to support the hopper door 10 on one side of the center sill independently of the hopper door on the opposite side of the center sill.

A primary feature of the invention consists in providing each of the hopper doors 15 with rigid means and in associating therewith means movably mounted on opposite sides of each hopper for engaging the said rigid means to maintain the door in closed position.

20 A further feature of the invention resides in providing a hopper car door with mechanism involving a plurality of members respectively secured to the door adjacent opposite edges thereof and a U-shaped member 25 pivotally connected to the car adjacent each of said door members for engagement with the latter to support the door in closed position.

25 A still further feature of the invention consists in providing a hopper door with members adjacent opposite edges thereof which project outwardly beyond adjacent portions of the hopper and terminate in upwardly projecting extensions, the outer edges of the 30 extensions being fashioned with spaced ledges, and in combining therewith, means pivotally connected to the sides of the hopper having portions cooperable with the upwardly projecting extensions of the door members for maintaining the door in either a partly closed or a fully closed position.

35 Other and more specific features of the invention residing in advantageous constructions and relations of parts will hereinafter appear and be pointed out in the claims.

40 In the drawings illustrating a preferred embodiment of the invention:

45 Figure 1 is a fragmentary side elevational view of a hopper and its coacting door showing the invention applied thereto.

Figure 2 is a fragmentary front elevational view of the construction illustrated in Figure 1, the relation of the hoppers on opposite sides of the car center sill (not shown) being disclosed.

55 Figure 3 is a sectional view taken on line 3—3, Figure 1.

The railway car to which the door locking mechanism embodying the invention is applied is of the well known type having hoppers disposed on opposite sides of the car center sills, the hinged axis of the hopper doors extending transversely of the car. This arrangement of hoppers is clearly shown by the portion of the car construction illustrated in Figure 2. As both of the hoppers are similar and as the invention is equally applicable to each, only one hopper and its associated door mechanism will be described.

60 The hopper may be constructed in the usual manner with inner and outer side sheets 1 and 2, respectively, and the slope or inclined bottom sheet 3, the outer ends or edges of the sheets defining the discharge opening of the hopper. A swinging door 4, which is hinged to the car body in any suitable manner (not shown) so as to swing to open position under the influence of gravity, serves to 65 close the discharge opening.

65 Rigidly secured to the door, as by rivets 5 adjacent each of its side edges, is a member or hook 6. These members may be advantageously of plate-like form, and each is preferably offset intermediate its ends, as at 7, to 70 pass around the outwardly projecting side marginal flanges 8 of the door. The outer ends of the members 6, which are spaced laterally outward from the adjacent portions of the hopper side sheets, terminate in substantially vertical portions 9 having upwardly projecting extensions 10. The outer edges of the extensions 10 are fashioned with upper and lower spaced ledges 11 and 12, respectively, connected by an intermediate inclined or beveled portion 13.

75 Pivotally mounted on the side sheets of the hopper adjacent the door members 6 is a substantially U-shaped door supporting member or latch 14. This pivoted member may 80 advantageously be formed from a flat bar 85

100

or strip of metal, the major portion thereof being normally disposed in a substantially horizontal plane. Adjacent its opposite ends, the bar is twisted to form substantially vertical portions 15. Interposed between the side sheets of the hopper and the respective end portions 15 of the member 14 are castings 16 serving to space the latter outwardly from adjacent portions of the hopper. Pivot rivets 17 are employed for connecting the ends of the member 14 to their associated castings, the latter being rigidly connected to the side sheets by rivets 18. The castings 16 secured to the outer side sheet 2 may advantageously be provided with a pivoted cam 19 adapted to engage with an adjacent portion of the member 14 to lock the latter in door supporting position thereby preventing accidental opening of the door.

The legs or side portions 20 of the U-shaped member are formed with apertures 21 for respectively receiving the upwardly projecting extensions 10 of the door members to maintain the door in a plurality of positions of closure. The transversely extending portion 22 of the member 14 affords means enabling simultaneous operation of the leg portions 20 thereof, so as to secure the door at its opposite edges. When the door is permitted to swing open upon movement of the member 14 to an inoperative position, the portion 22 serves to limit opening movement of the door by contacting with its outer face.

The upwardly projecting extensions 10 of the member 6 are arranged to cooperate with the legs 20 of the latch member 14 in a manner such that when the door is permitted to swing open or is being moved to fully closed position, it will at all times maintain the latch member in an elevated position, thus insuring proper functioning of the mechanism. When it is desired to close the door the operator may grasp any convenient portion thereof moving it in the proper direction until the upwardly projecting extensions 10 are brought into registering alignment with the corresponding apertures 21 of the pivoted member; the latter will then drop and, by co-operating with the upper ledge 11, sustain the door in a position of partial closure. A downwardly directed force is then applied to any desirable portion of the pivoted member 14, causing the portions of the apertures 21 adjacent the outer edge of the extensions 10 of the door members to ride along the intermediate inclined portions 13 thereof, thus forcing the door into fully closed position in which position it will be maintained when the member 14 cooperatively engages the lower ledge 12.

As the inner edge of the door, when it is being moved from open to partially closed position, tends to lag behind the outer edge thereof, the upper ledge 11 of the member 6 secured to the inner edge of the door is spaced

inwardly from a vertical plane parallel with the hinged axis of the door and passing through the upper ledge of the member 6 adjacent the outer edge of the door. In this manner the upwardly projecting extensions 10 of each of the members 6 are adapted to substantially simultaneously cooperate with the apertures 21 of the member 14 to maintain the door in a partial position of closure.

From the foregoing it will be perceived that, in addition to permitting independent operation of the doors of the hoppers disposed on opposite sides of the center sill, the mechanism disclosed efficiently functions to support the opposite side edges of the door in a manner such that accidental loss of fine lading is prevented.

I claim:

1. In a railway car having hoppers disposed transversely of the car, a hinged door for each of said hoppers, the hinge axis of said doors extending transversely of the car and the doors being adapted to swing to open position under the influence of gravity, and door supporting mechanism for each hopper involving a plurality of members respectively secured to the hopper door adjacent the opposite sides thereof and a member pivotally mounted on the sides of the hopper and respectively engageable with said members on the door for maintaining said door in closed position, said member having a portion extending from one side of the hopper to the other and spaced from the closed door in the direction of opening movement thereof.

2. In a railway car having hoppers disposed transversely of the car, a hinged door for each of said hoppers, the hinge axis of said doors extending transversely of the car and the doors being adapted to swing to open position under the influence of gravity, and door supporting mechanism for each hopper involving members respectively secured to each door adjacent opposite edges thereof, a substantially U-shaped member secured adjacent its opposite ends to the respective sides of the hopper, said member having portions adapted to engage the members secured to the door for supporting the latter in closed position.

3. In a railway car having a lading discharge opening, a hinged door for closing said opening, the door being movable to open position under the influence of gravity, and door supporting mechanism involving brackets secured to the door and a substantially U-shaped member having its ends respectively pivotally secured to the car adjacent opposite edges of the door, the legs of said U-member being adapted to cooperate with the said brackets to maintain the door in closed position.

4. In a railway car having a hopper provided with a lading discharge opening, a hinged door for closing said opening, the

door being movable to open position under the influence of gravity, and door supporting mechanism involving a plurality of members respectively secured to the door adjacent opposite edges thereof and projecting outwardly therebeyond and a number pivotally connected to the hopper adjacent each of said door members for cooperating with the latter to maintain the door in a plurality of positions of closure, said member having a portion normally spaced from the closed door adapted to limit opening movement of the door.

5. In a railway car having a hopper provided with a lading discharge opening, a hinged door for closing said opening, the door being removable to open position under the influence of gravity, and door supporting mechanism involving a plurality of members respectively secured to the door adjacent opposite edges thereof, each of said members having an upwardly projecting extension and a member having its ends pivotally connected to opposite sides of the hopper adjacent each of said door members and having portions cooperable with the upwardly projecting extensions of the latter to maintain the door in closed position.

6. In a railway car having a hopper provided with a lading discharge opening, a hinged door for closing said opening, the door being movable to open position under the influence of gravity and door supporting mechanism involving a plurality of members respectively secured to the door adjacent opposite edges thereof, each of said members having an upwardly projecting extension disposed outwardly of the respectively adjacent sides of the hopper, and a substantially U-shaped member secured to opposite sides of the hopper, said last-named member having apertures for receiving the upwardly projecting extensions of the respective door members for maintaining the door in closed position.

7. In a railway car having a hopper provided with a lading discharge opening, a hinged door for closing said opening, the door being movable to open position under the influence of gravity, and door supporting mechanism involving a plurality of members respectively secured to the door adjacent opposite edges thereof and having portions projecting therebeyond, and means pivotally connected to the hopper adjacent each of said door members and cooperating therewith for maintaining the door in closed position, said outwardly projecting portions of the door members being adapted to sustain the pivoted means in an elevated position when the door is in open position.

8. In a railway car having a lading discharge opening, a hinged door for closing said opening, the door being movable to open position under the influence of gravity, and door supporting mechanism involving means

secured to the door and a member pivotally mounted on the car body for cooperating with the said means for maintaining the door in closed position, said pivoted member having a portion normally spaced from the outer face of the closed door for limiting opening movement thereof.

9. In a railway car having a lading discharge opening, a hinged door for closing said opening, the door being movable to open position under the influence of gravity, and door supporting mechanism involving a plurality of members respectively secured to the door adjacent opposite edges thereof and having portions projecting outwardly therebeyond and a member pivotally secured to the car body adjacent each of said door members for cooperating therewith to maintain the door in closed position, said pivoted member having a portion normally overlapping the outer face of the door to limit opening movement thereof and the outwardly projecting portions of said door members being adapted to respectively cooperate with said member to maintain the latter in an elevated position.

10. In a railway car having a lading discharge opening, a hinged door for closing said opening, the door being movable to open position under the influence of gravity, and mechanism for supporting the door in closed position involving a member rigidly mounted on the door and a member pivotally mounted on the car body, the said door member being provided with an upwardly projecting plate-like extension disposed outwardly of the adjacent edge of the door in a plane substantially normal to the hinge axis of the door, said pivoted member having portions adapted to respectively engage the outer edge of said plate-like extension and to overlap a side face thereof when the door is supported in closed position.

11. In a railway car having a lading discharge opening, a hinged door for closing said opening, the door being movable to open position under the influence of gravity, and door supporting mechanism involving a member rigidly secured to the door and having an upwardly projecting extension disposed outwardly of a side edge of the door and a member pivotally secured to the car body having an aperture for receiving the extension of the door member to maintain the door in closed position.

12. In a railway car having a lading discharge opening, a hinged door for closing said opening, the door being movable to open position under the influence of gravity, and door supporting mechanism involving a member rigidly secured to the door and having a substantially vertical plate-like portion disposed outwardly of a side edge of the latter in a plane substantially normal to the hinge axis of the door, the outer edge of said plate-like portion being provided with a plurality

of spaced ledges, and a member pivotally secured to the car having a portion cooperable with the ledges of the door member to maintain the door in partially closed or in fully closed position.

5 13. In a railway car having a lading discharge opening, a hinged door for closing said opening, the door being movable to open position under the influence of gravity, and door supporting mechanism involving a member rigidly secured to the door and having an upwardly projecting extension disposed outwardly of a side edge of the door, the outer edge of said extension being provided with spaced ledges, and a member pivotally mounted on the car body having an aperture for receiving said extension and cooperating with the ledges thereof to support the door in a partially closed or in a fully closed position.

13 14. In a railway car having a leading discharge opening, a hinged door for closing said opening, the door being movable to open position under the influence of gravity, and door supporting mechanism involving a plurality of members respectively secured to the door adjacent opposite edges thereof, each of said members having an upwardly projecting extension disposed outwardly of the adjacent edge of the door, the outer edge of each extension being provided with a plurality of ledges, and a pivoted U-shaped member having its ends connected to the car body adjacent said door member, said pivoted member being fashioned with apertures for respectively receiving the upwardly projecting extensions of the door members to support the door in a partially closed or in a fully closed position.

14 15. In a railway car having hoppers disposed transversely of the car, a hinged door for each of said hoppers, the hinge axis of said doors extending transversely of the car and the doors being adapted to swing to open position under the influence of gravity, and door supporting mechanism for each hopper involving a plurality of members respectively secured to each door adjacent opposite edges thereof, each of said members having an upwardly projecting extension provided on its outer edge with spaced ledges, and a U-shaped member pivotally connected to opposite sides of each hopper having an aperture for receiving the upwardly projecting extensions of the associated door members to support the door in partially closed or in fully closed position.

15 16. In a railway car having hoppers disposed transversely of the car, a hinged door for each of said hoppers, the hinge axis of said doors extending transversely of the car and the doors being adapted to swing to open position under the influence of gravity, and door supporting mechanism for each hopper involving a plurality of members respective-

ly secured to its associated door adjacent opposite edges thereof, each of said members having upwardly projecting extensions disposed outwardly of the adjacent side of the hopper, the extensions being fashioned with 70 upper and lower ledges connected by an intermediate inclined portion, and a U-shaped member pivotally connected to the sides of each hopper having apertures for respectively receiving the said extensions of the door members to cooperate with the upper and lower ledges thereof to maintain the door in partially closed or in fully closed position, respectively, the inclined portions of the door members being adapted to cooperate with the apertured portions of the pivoted member so that movement of the latch from the said upper ledges to the said lower ledges will force the door to fully closed position.

In testimony whereof I affix my signature. 85
